8940x William Wadsworth
Letters Patent

The schedule referred to in this Letters Patent and making part of the same containing a description in the words of the said William Wadsworth himself of his improvement in a machine for manufacturing, pressed brick called the Improved Brick Press. To all people to whom these presents shall come, William Wadsworth of Hartford in the County of Hartford and State of Connecticut greeting. Be it known that I the said William Wadsworth have invented, made, devised, constructed and applied to use a new and useful improvement in a machine for manufacturing pressed brick which I call the Improved Brick press, by which pressed brick can be made in a more perfect and expeditious manner than in any mode hitherto known and used. My improvement consists in a combination of machinery, all the separate parts of which may have been heretofore known or used separately, or for other purposes, and the new combination for a new purpose, to effect an improvement in a valuable art, constitutes my invention for which I pray that the exclusive use may be secured to me according to the provisions of law. Herewith is forwarded to the Patent Office a model and two sets of drawings by reference to which this specification can readily be understood. My machine is represented by the model and drawing as on four wheels, and it will be usually convenient to have it on wheels of convenient height, that it may be moved over the brick yard, that the bricks may be pressed by the spot where it is intended to deposit them. I make a substantial frame of sound wood, cast iron or other material, about five feet in length, and about twenty inches in width with strong posts at the corners & cross pieces, the front part being solid to meet the fixtures on the axletree about eighteen inches high from the bottom of the wheels. The frame must be sufficiently strong, and well fastened to support the machine, and the strain in the operation. The tops of the posts are raised about two & a half inches above the

side pieces and ends of the frame. The sides and ends of the frame are marked A, A, A, A, across the side frame timber under the upright posts for sustaining the leaves. B. is a strong cross piece of timber or other material fastened to the side pieces of the frame by bolts or in any other convenient mode, to strengthen and sustain the frame under the upright posts. The end is seen in the drawing, & marked a. The frame must be made perfectly smooth on the top except the corners. C & D. are two pieces of cast iron or other suitable metal, which I call the bed pieces. They may be about two or three inches deep & about two inches wide or ~~any other dimensions~~ that experience may be found to prefer. They are about five inches apart and extend the whole length of the frame to which they must be well secured. They are raised about three quarters of an inch above the frame, except that part where the plate C. is let into them. They must form a smooth surface with the plate C. The ends of the bed pieces must be stout and strong, and rise about five and a half inches. The ends D. are perforated with one & a half inch holes to receive the guides on the stationary end of the horizontal toggle joint; the ends E. rise about the same height. The ends and bed pieces must be large and strong enough to bear the whole strain in pressing the brick without trembling. C is a plate of cast iron or other material, seventeen inches long, and nine inches wide. Three mortons of an inch deep are cut into the bed pieces to which it is securely fastened. This plate has wings extending from the outer edge of the front side of it, four inches wide and two inches long coming to the front end of the frame. These wings lie on the outside of the bed pieces adjoining them, and of even height with them. The end of this is to support the elevations L. L. & P. P. likewise operates as a brace and supports to the bed pieces. It is an upright sustaining post of cast iron or other suitable material rising from one of the bed pieces about three feet six inches high, on other similar part rises from the other bed pieces. The edge of which is only visible in the drawing, this must be connected by an iron bar at the top just below which are circular enlargements of the post through which

8940X

are one and a half inch holes to receive the quoins on the upper end of the perpendicular toggle joints. C. is an upright wooden part at one end of the machine rising from the frame and connects with the former named upright posts by a bolt b. b. to steady it. In this wooden part is a slot a through which passes the lever H. This slot must extend high enough to let the lever rise to a level and low enough to let it descend so far as to bring the toggle joints straight. H. is the lever of wood or other material that works the toggle joints and affects the pressure on the bricks it passes through the upper part of the perpendicular toggle joint just above its centre joint where it is secured fast. This toggle joint where the lever passes through it is enlarged as is represented on the drawing a. a. for the purpose of securing a better purchase to the lever - b. b. is a weight fastened to one end of the working lever of sufficient size to balance it. I. I. is the perpendicular toggle joint which turns on guides passing through the upright sustaining posts jointed in the middle in the usual manner and secured to the horizontal toggle joint close by its center joint by a bolt on which it works for this purpose there is an elevation in the horizontal toggle joint of the height of one and a half inch. The center of this is cut down to receive a tenon which is made on the lower end of the perpendicular toggle joint through the elevation and tenon a hole is made of suitable dimensions to receive a bolt to connect the toggle joint on which bolt the perpendicular toggle joint works. J. J. is the horizontal toggle joint secured stationary at D. as before described but moveable at the attack end where it is secured by a suitable mortise & tenon by a bolt to the bar or follower K. the toggle joints are of cast iron or any other metal and of any required size. P. P. P. P. are braces of cast iron or other suitable material proceeding from the bed pieces to the upright sustaining posts to strengthen them. R. is a moveable horizontal bar or follower secured at one end to the horizontal toggle joint as aforesaid made of cast iron or other suitable material. The width of three inches. The depth of two inches. R. is two elevations of cast iron or other suitable material. The one at the edge of the plate C.

C. the other which in the drawing is nearly concealed by the mould. There are two others similar to them on the other side of the plate, all four of which are cast on the plate C., they are raised high enough to receive the moveable bar or follower & through which it passes in spaces cut large enough for it to move freely in, secured in those spaces by straps of iron passing over by some in the tops of the elevations marked C. in fig. is what I call the biddle & brace. Call the brace, these armards of wrought iron, are to move forward and back the mould A. which receives and holds the brick while in the process of pressing. The biddle-gr. is fastened by bolts or screws to the outside of the lower parts of the mould A. on each side of it and the brace h. is in the like manner fastened to the upper side of the mould A. Their rise is a slope as appears by the drawing, and model to the requisite height where they are firmly fastened together. There the brace stops and hence the biddle pieces change their direction and proceed back horizontal by over a roller between the upright sustaining posts marked O.

The sides of the bridle, where it proceeds horizontally, are about two inches apart at the commencement of the horizontal part. They are secured by a permanent bolt-back of which are two cast-steel rollers on which the dog is fastened to the beam. It plays. These rollers are scarcely visible on the drawing, but may be readily understood by the following description. They are placed about two inches apart between the sides of the bridle supported by guides and passing through the sides of the bridle so formed that they will readily turn round. The cog A. at its lower end ordinarily acts between these two rollers. The beam T. is attached to the perpendicular toggle joint one inch above the centre joint, extending twelve inches parallel with it. The dog B. is fixed on the beam by a socket and wedge to adjust it at pleasure in the manner represented by the model & drawings. When the lever C. is bent down the lower end of the dog B. is brought against the front roller between the sides of the bridle and carries it with the mould. The forward end of it encloses the block & which brings it to the point where the pressure is given to the bridle at which point the lever

end of the dog rises over the front roller and projects freely so far as may be necessary in conveying the working lever to the lower end of the slot. When the lever is raised upon the lower end of the dog will press on the front and stroke the back roller between the sides of the brick and bring it back to the position represented in the drawing, and without this would far enough to receive another brick for pressure and then the dog will rest against the back roller and remain stationary till the downward pressure of the same will bring the dog again in contact with the forward roller. The mould ^{and two ends} is a box of two sides made of suitable thickness of cast iron or other material of the necessary thickness of the capacity required to enclose and hold the brick to be pressed in. Three inches and three-quarters in width lined with iron & steel plates three eighths of an inch in thickness, on their front bottom part of the mould is an open box ^{about a half inches} broad with an elevation on one end both serve for a stop and guide to the brick, and are even with the inner surface of the mould and when the impuff is given the brick they press under and by the plates ^{h. a. m.} at the end of the bar or follower. ^{h.} which is in the drawing is concealed in the mould. ^{h.} is a cast iron plate three quarters of an inch thick, cogged with iron and steel plates three eighths of an inch thick, fastened securely to the end of the bar or follower, ^{h.} which shall exactly fill the mould. ^{h.} is a cast iron plate of the same size as the one on the follower and cogged with iron & steel in the same manner over which the mould ^{h.} shall pass when it is pressed forward by the dog & the plate ^{l.} corresponds with the plate ^{h.} as does plate ^{m.} The plate ^{m.} is secured to the ends ^{b.} by solid and sufficient screws passing through the iron ^{c.} and the plates ^{b. & c.} are secured to the plate ^{m.} by a screw attached to the centre of plate ^{b.} passing through an aperture in the centre of plate ^{m.} by a nut and washer on the opposite side. Between the plates ^{m.} & ^{c.} may be introduced at pleasure thin sheets of copper or sheet iron or any other material to regulate the thickness which is desired for the brick to be pressed.

etc. The plate K is moved to plate L by screws one at each corner and moves a set of slides of C. These are other material cast on the moulds moving with it, and upon the alterations cast on the plate C, on which it moves. There are corresponding rails and fixtures on the other side not exhibited on the drawing. By means of this machinery, on the drawing represented as far enough to receive the brick to be pressed. The brick is to be placed between the plate K and the mould M, which may readily be done so that on pressing the lever H the mould M shall press over the brick and cause it perfectly so that it shall be in the mould, be tween the plate K and the one on the following is done on the mould. Then by pressing down the working lever H by hand power. The two toggle joints will be caused till they are both made perfectly straight. The horizontal toggle joint being entirely level and the perpendicular toggle joint being perfectly straight between the two upright sustaining posts.

This pressure will gradually increase, and at the point where it terminates it will be increased by the evenly pressure of a single hand on the lever to give a power and pressure on the brick almost beyond calculation, and enough to press the brick to any desired degree. On testimony that the foregoing is a true specification of my said improvement I have caused set my hand the eighteenth day of March in the year of our Lord one thousand eight hundred and thirty seven.
